UNITED STATES PATENT OFFICE.

GEORGE HERBERT KING, OF WOODSTOCK, ONTARIO, CANADA.

VACUUM-CLEANER.

1,054,354.

Specification of Letters Patent. Patented Feb. 25, 1913.

Application filed January 18, 1912. Serial No. 671,088.

To all whom it may concern:

Be it known that I, GEORGE HERBERT KING, of the city of Woodstock, in the county of Oxford, in the Province of Ontario, Canada, have invented certain new and useful Improvements in Vacuum-Cleaners, of which the following is the specification.

My invention relates to improvements in vacuum cleaners and has for its object to provide a structure which is compact, simple and efficient and one which is comparatively inexpensive to manufacture.

The above and other objects will be apparent when the specification is considered together with the accompanying drawings, in which—

Figure 1, is a vertical section through the vacuum chamber and co-acting parts. Fig. 2, is a similar view to Fig. 1 taken at right angles thereto. Fig. 3, is a perspective detail of the securing device for the vacuum chamber closure.

In the drawings like letters of reference indicate corresponding parts in each figure.

A is the vacuum chamber provided with a dust inlet tube A' connected in the usual manner to a suitable dust collecting nozzle. The vacuum chamber comprises a bottom board A², side walls A³ and end walls A⁴ and A⁵ and a top cap or closure A⁶ detachably secured to the top of the chamber by means which I will hereinafter describe.

The vacuum chamber rests upon the main board D on the extended end D' of which the operator stands.

F and F' are bellows secured to the end boards A⁴ and A⁵ of the vacuum chamber.

F² and F³ are ports extending from the lower end of the bellows through the boards A⁴ and A⁵ to below the board A² so as to communicate with the atmosphere.

F⁴ are valves for the ports F² and F³.

F⁶ is an intermediate wall extending across the vacuum chamber intermediately of its height.

F⁷ is an orifice extending through the wall F⁶.

F⁸ is a vertical wall extending upwardly from the wall F⁶ in proximity with the top of the vacuum chamber.

G are ports extending into the vacuum chamber between the wall F⁸ and one of the walls A³ of the chamber. The ports G are provided with valves G'. It will be under-

stood on referring to Fig. 1 of the drawings that the ports G connect the top portion of each bellows F and F' to the vacuum chamber.

J is an operating lever connected by a link J' to the bellows F. The bellows F and F' are provided with depending lugs J² connected together by a link J³.

K are a series of screens extending horizontally over the orifice F⁷ between one end board A³ and the wall F⁸.

K' is an arc-shaped spring against which the cap A⁷ is held so as to hold the screens tightly down in place.

The construction which I have hereinbefore described is covered by a previously filed application. I have only described such construction so as to show the connection of the parts which I now claim to be new therewith. Such novel parts I will now describe.

L is a bag formed of cotton or other suitable material suitable for screening the dust. The bag L extends around the orifice F⁷ and is secured thereto at the top to the edge 80 of the opening F⁷ by a suitable frame L'.

M is a straight deflecting board which extends downwardly at an obtuse angle to the intermediate wall F⁶ so that as the dust laden air enters through the inlet A' it strikes against the board M and is deflected downwardly in the direction of arrow and then upwardly through the depending screening bag L.

It will, of course, be understood that the heavy dust falls to the bottom of the chamber A while the lighter dust is carried upwardly and is caught by the screening bag L. The screening bag L will prevent the screens by continued operation of the machine becoming clogged. As the interstices become clogged the bag will alternately be drawn up and released so as to pulsate with the suction of the machine thereby automatically shaking itself free of dust.

N is a board extending between the wall F⁸ and one of the walls A³ and from the wall A⁴ to the wall A⁵. The board N is provided with suitable perforations N' and N² is a layer of suitable filtering fabric which is preferably folded in several layers and laid on top of the board N so as to cover the perforations N'. By this means the filtering material is spread over a wide area and is not held compactly in a pocket as was

the case in my previous construction thereby preventing air passing freely through and making the machine hard to work.

5 O are plates secured to each corner of the closure or cap A⁶. The plates O are provided with inclined portions O' terminating in depressions O².

10 P is a bail forming a handle P'. The ends of the bail extend downwardly at P⁵ to each side of the vacuum chamber A and are pivotally connected thereto by any suitable screws P². Between the handle P' and the downwardly extending portion P⁵ is a horizontal portion P³. It will be understood 15 that when it is necessary to remove the cap or closure the handle P' is forced outwardly so as to swing the bail P on its pivot formed by the screws P² and thereby force the horizontal portion P³ out of the depression O². 20 When it is desired to again place the closure into position the handles P' are forced together so that the horizontal portions P³ engage the inclined portion O' of the plates O and by the continued inward movement 25 of the handle P' such portions P³ are forced into the depressions O².

It will be seen from this construction that each corner of the closure or cap is held down tightly against the top of the wall of 30 the casing, thereby preventing any liability of the cap warping up at the corners, thus rendering the vacuum chamber leaky and

destroying the inward suction of the air to draw the dust through the tube A into the chamber.

35

From this description it will be seen that I have devised a very simple means whereby any danger of clogging the screens and obstructing the passage of air through the filtering material is obviated, thereby rendering the work of the machine more easy and preventing any danger of the deflector board becoming clogged or the casing leaky.

40

What I claim as my invention is.

45 In a vacuum cleaner, the combination with the vacuum chamber, of an intermediate cross wall having an orifice therein, a vertical wall extending upwardly from the intermediate wall in proximity with the top of the cleaner and between the end boards 50 of the vacuum chamber, a suction port located in the end walls above the cross wall and between the vertical wall and the wall of the vacuum chamber, and a perforated cross wall extending between the vertical 55 wall and the wall of the vacuum chamber, and a layer of filtering material designed to cover the perforated cross wall, as and for the purpose specified.

GEORGE HERBERT KING.
